UNITED STATES PATENT OFFICE

SWITS CONDÉ, OF OSWEGO, NEW YORK.

DESIGN FOR KNIT DRAWERS.

Specification forming part of Design No. **11,462**, dated October 21, 1879; application filed September 26, 1879.
[Term of patent 7 years.]

To all whom it may concern:

Be it known that I, SWITS CONDÉ, of Oswego, in the county of Oswego, in the State of New York, have invented new and useful Improvements in Designs for Plain Knit Drawers, of which the following, taken in connection with the accompanying drawing, is a full, clear, and exact description.

The accompanying drawing represents a pair of drawers knitted to present what is termed a "plain face"—*i. e.*, free of ribs.

a and *a'* denote plain, colored, and mottled stripes, respectively, the mottled stripes being generally composed partly of the color of the plain stripes. These stripes are arranged perfectly straight and parallel to each other, and vertically in relation to the garment.

What I claim as my invention is—

The design for plain knit drawers, consisting of straight, mottled, and plain stripes arranged alternately and parallel to each other, and vertically in relation to the garment, substantially as described and shown in the accompanying illustration.

In testimony whereof I have hereunto signed my name in the presence of two attesting witnesses, at Oswego, in the county of Oswego and State of New York.

SWITS CONDÉ. [L. S.]

Witnesses:

EDW. MAXWELL,
FRED L. CONDÉ.
